UNITED STATES PATENT OFFICE

JOHN FRANCIS RYAN, OF TAGGERTY, VICTORIA, AUSTRALIA.

COMBINATION-TOOL.

1,287,446.

Specification of Letters Patent.

Patented Dec. 10, 1918.

Application filed September 24, 1918. Serial No. 255,413.

To all whom it may concern:

Be it known that I, JOHN FRANCIS RYAN, a subject of the King of Great Britain, residing at Taggerty, in the State of Victoria, Australia, have invented certain new and useful Improvements in Combination-Tools; and I do declare the following to be a full, clear, and exact description of the invention, such as will enable others skilled in the art 10 to which it appertains to make and use the same.

This invention has been devised to provide a combination tool which will accomplish three distinct functions. In describing and 15 illustrating my invention I shall refer to a tool combination comprising a pick hoe and shovel. The peculiar construction of the instrument embodying my invention permits the same handle to be employed for each 20 respective class of work above mentioned. This arrangement will be appreciated by interested persons, inasmuch as that it dispenses with the necessity of having three separate tools, the handling is facilitated, the 25 weight of the combination tool is largely reduced in comparison with three separate tools and the former is easily carried to and fro from work and the possibility of mislaying one tool is obviated. The cost of manufacture 30 being small the combination tool may be made and sold at low price. In order that my invention may be the more easily understood reference will be made to the accompanying sheet of drawings in which:—

35 Figure 1 illustrates the combination tool being employed as a pick or hoe;

Fig. 2 illustrates the handle in position when it is desired to perform shoveling work;

40 Fig. 3 illustrates the combined tool with the handle removed, while

Fig. 4 is an enlarged sectional view of the head hereinafter referred to.

In the accompanying drawings a combination tool is illustrated in which *a* is a pick, and *b* a shovel and hoe. Integral with such formation is a head *c* constructed to provide tapering recesses *d* and *d'* disposed at right angles to each other.

50 When it is desired to use the tool as a shovel, the tapering circular end of the handle *f* is inserted in the direction indi-

cated by the arrow, see Fig. 2, and driven home in the recess *d'*, and if it is desired to use the tool as a pick or hoe (see Fig. 1) the handle is inserted in the direction indicated by an arrow and its enlarged end fastened in the recess *d*. If desired a suitable screw *e* passing through the threaded slots *e'* may be employed as additional fastening means 60 to retain the handle *f* firmly in position.

It is obvious that head *c* may be varied in its formation, and the configuration of the recesses *d* and *d'* provided therein may be formed to correspond with the required 65 shape of the securing end of the handle *f*. I would also have it understood that a combination of tools other than a pick hoe and shovel may be employed without departing from the ambit of my invention.

I claim as my invention:

1. As a new article of manufacture, a combination tool comprising a tool member, a head centrally secured thereto and having therein a tapered straight sided socket and 75 also a round socket, and a handle adapted at one end to fit the tapered straight sided socket and at the other end to fit the round socket.

2. As a new article of manufacture, a combination tool comprising a tool member, a head centrally secured thereto and having therein a tapered straight sided socket and also a round socket, a handle adapted at one end to fit the tapered straight sided socket 85 and at the other end to fit the round socket, and means for securing the handle in place in the said sockets.

3. As a new article of manufacture, a combination tool comprising a tool member, a head secured centrally thereto and having a tapered straight sided socket placed there-in transversely of the tool and also a round socket therein placed longitudinally of the tool, and a handle adapted at one end to fit 90 the tapered straight sided socket and at the other end to fit the round socket.

4. As a new article of manufacture, a combination tool comprising a tool member, a head secured centrally thereto and having a 100 tapered straight sided socket placed therein transversely of the tool and also a round socket therein placed longitudinally of the tool, there also being holes placed trans-

versely in the said head and at right angles to the round socket therein, a handle adapted at one end to fit the tapered straight sided socket and at the other end to fit the round socket, and a bolt adapted to pass through the said holes in the head to secure the handle in position in the said sockets.

In testimony whereof I have signed my name to this specification in the presence of two subscribing witnesses.

JOHN FRANCIS RYAN.

Witnesses:

A. O. SACHSE,
AUGUSTINE THOMAS MADDEN.
